UNITED STATES PATENT OFFICE.

EDMUND C. MORGAN, OF CHICAGO, ILLINOIS.

APPARATUS FOR LOADING COAL.

1,304,084.

Specification of Letters Patent. Patented May 20, 1919.

Continuation in part of application Serial No. 611,603, filed November 10, 1896. (Patent No 1,116,356, dated November 3, 1914.) This application filed September 3, 1914, Serial No. 859,976. Renewed August 24, 1918. Serial No. 251,339.

To all whom it may concern:

Be it known that I, EDMUND C. MORGAN, a citizen of the United States, residing in Chicago, Illinois, have invented certain new and useful Improvements in Apparatus for Loading Coal, of which the following is a specification.

My invention relates to loading apparatus and one of its objects is the provision of suitable and efficient means for scooping coal or other material from the floor of very low-roofed mines and loading such material into mine cars.

Other objects of the invention will appear hereinafter, the novel features and combinations being set forth in the appended claims.

In the accompanying drawings, Figure 1 represents an embodiment of my invention in elevation; Fig. 2 is a front view of the machine shown in Fig. 1; Fig. 3 is a plan view of Fig. 1; Fig. 4 is an elevational view partly in section showing the side of the machine opposite that shown in Fig. 1; Fig. 5 is an elevational view illustrating the manner in which the coal is removed from the scoop; Fig. 6 is a plan view of Fig. 5; Fig. 7 is a sectional elevational view of a modification in which the scoop is integral with one of the rack bars at each side of the machine; and Fig. 8 is an enlarged fragmentary view showing a fixed stop for limiting the forward movement of the apron which effects the removal of the coal from the scoop.

Referring to Figs. 1, 2, and 3, it will be seen that the main frame 9 is mounted on wheels 10 to form a truck for supporting the shoveling mechanism. An electric motor 11 is connected by its shaft 12, worm 13 and worm gear 14 to a short transverse shaft 15 which is mounted in suitable bearings 16. Mounted loosely on the shaft 15 are the bevel gear wheels 17 and 18 each meshing with the bevel gear 19 mounted at the lower end of the diagonal shaft 20 which is in turn mounted in the bearing 21 at the upper end of the standard 22 as shown in Fig. 4. By means of friction clutches 23 and 24 the gears 17 and 18 may be operatively connected to the gear 19. The clutches 23 and 24 are connected by the crosspiece 25 so that when one clutch is engaged the other is released. By means of a lever 26 fulcrumed at 27 and pivotally connected to the crosspiece 25 at 28, the clutch 23 may be engaged or disengaged with the gear 17 and the clutch 24 may be engaged or disengaged with the bevel gear 18. By means of this mechanism the electric motor may be permitted to be rotated constantly in the same direction while reverse rotation may be given to the gear 19 and the shaft 20 connected thereto. However, it should be understood that the electric motor 11 may be provided with any suitable and well-known electric reversing switch and controlling mechanism.

The upper end of the inclined shaft 20 is provided with another bevel gear 29 which meshes with the gear 30 as shown in Figs. 2 and 4. The gear 30 is keyed to the transverse shaft 31. This shaft 31 extends entirely across the machine and is mounted in the bearings 32, 32 as shown in Fig. 2. At the outer ends of the transverse shaft 31 are sprocket wheels 33, 33 engaged by the sprocket chains 34, 34. The sprocket chains 34, 34 are also geared to sprocket wheels mounted on the axles of the rear wheels 10, 10. The axles of the wheels 10, 10 are mounted in the bearings 35, 35 as shown in Fig. 2. The bearings 35, 35 are connected rigidly to the main frame 9. The bearings 32, 32 are mounted at the upper ends of the standards 36, 36 which are also rigidly connected to the main frame 9.

Pivoted to the main frame 9 as shown at 37 in Fig. 1 is a supplemental frame 38 adapted to swing laterally to either side of its central position. I prefer to provide anti-friction rollers 39, 39 between the supplemental frame and the upper portion of the main frame, although a sliding connection may be provided if desired. Furthermore, a track 40, arc-shaped as shown in Fig. 3, may be provided particularly when the rollers 39, 39 are omitted, so that friction may be reduced.

The supplemental frame 38 is U-shaped in cross section and open at both its forward and its rearward ends so as to form a flat bottom trough or chute with vertical side walls so that the coal may be brought to the forward end of the supplemental frame and then loaded into mine cars out of the rear end of the supplemental frame after being forced longitudinally therethrough.

The means for scooping up the coal comprises a scoop 41 which is provided with vertical sides and with flat bottom and is

open at its rear end. This scoop fits into the forward end of the supplemental frame as shown in Fig. 1 and its lip 42 rests on the platform 43 which is detachably connected at 44 to the main frame 9. If the platform 43 is omitted the downward movement of the lip 42 will be limited by the forward end 45 of the bottom of the supplemental frame. Furthermore, the scoop is under full control of the operator and if the lip 42 in moving forward should meet an obstacle or considerable resistance, the scoop may be lifted or retracted.

The scoop 41 is pivoted by means of pintles 46, 46 to the vertical side plates 47, 47 of the supplemental frame 38, as shown in Fig. 3. On one of the pintles 46 is mounted a worm gear 48 which meshes with the worm 49. The worm 49 is carried on a vertical shaft to the upper end of which is connected the bevel gear 50 and to the lower end of which is connected the bevel gear 51. Meshing with the gears 50 and 51 is a bevel gear 52 carried at the forward end of a shaft 53 which is square in cross section and slidable in the hollow shaft 54. The sliding rod or shaft 58 fits into a corresponding recess or bore in the rear end of the hollow shaft 54. The shaft 53 fits into a similar recess or bore in the forward end of the hollow shaft 54. The hollow shaft 54 is mounted in suitable bearings 55, 56 and 57, so that when the electric motor 11 is operated, motion will be transmitted through the shaft 12, gears 63, 62, flexible connections 61, 60, 59 and rod 58 to said hollow shaft 54. Rotary motion of the hollow shaft 54 will thus be transmitted to the sliding shaft 53, thereby rotating the gear 52 and the gears 50 and 51. The gears 50 and 51 being mounted loosely on the vertical shaft to which the work 49 is keyed, motion to the latter is not transmitted until either the friction clutch 64 or 65 is operated. A yoke 66 is fulcrumed at 67 and connected to the operating lever 68 so that when the latter is moved down the clutch 65 will be engaged and when the lever 68 is moved up the clutch 64 will be engaged. By this arrangement the scoop 41 may be positively lifted or lowered whenever desired. If the platform 43 is omitted and the lip 42 of the scoop 41 is moved over rough ground the lifting clutch may be operated whenever desired to lift the forward end of the scoop while moving forward; or, if desired, the lifting clutch may be operated with such pressure that slipping will be permitted at the clutch while the lip of the scoop is held off the ground at any desired elevation while the scoop is being moved forward.

I will now describe the arrangement for effecting the loading of the coal or other material from the shovel to the mine car. It will be observed that the chute or way is not arranged upon an incline but the shovel

41 is arranged to slide longitudinally with respect to the chute which is formed by the bottom and vertical sides of the supplemental frame 38. Suitably mounted in the supplemental frame are rack bars 69, 69 70 having pivotally mounted upon the forward ends thereof an ejector 70. Any suitable or convenient arrangement of gearing for positively swinging said ejector at will may be provided. An illustration of a suitable and 75 convenient arrangement of gearing is shown in the drawings as being similar to that shown for tilting the scoop. This arrangement of gearing comprises a worm wheel 71 mounted on the ejector shaft 72 near the 80 outer end of one of the rack bars 69 as shown in Figs. 1 and 2. The worm wheel 71 meshes with the worm 73 which is keyed to a vertical shaft on which are journaled the bevel gears 74 and 75 which mesh with the bevel 85 gear 76. The latter is connected to the outer end of the squared shaft 77 which slides in the outer end of the hollow shaft 78. The latter is mounted in the bearings 79, 80, and 81, on the supplemental frame. Extending 90 into the rear end of the hollow shaft 78 is another squared shaft 82 which is connected by the universal joints 83 and 84 and a connecting rod 85 to the gear wheel 86 which is journaled on a bearing carried by the standard 87 mounted on the main frame 9. The gear 86 meshes with the gear 62 which in turn meshes with the gear 63 on the motor shaft 12. It is therefore evident that whenever the electric motor 11 is operated motion 100 will be transmitted through the shaft 12, gears 63, 62, 86, flexible connections 83, 84, and 85 to the square rod 82 and thence to the hollow shaft 78 and the squared shaft 77. When the shaft 77 is rotated the gear wheel 105 76 will transmit motion to the gears 74 and 75, but since the latter are loosely mounted on a vertical shaft carrying the worm 73 no motion is transmitted to the latter until either the clutch 88 or 89 is operated. A 110 yoke 90 is fulcrumed at 91 and connected to an operating lever 92. When the lever 92 is lifted the clutch 88 is operated and when the lever 92 is pushed down the clutch 89 is operated. It will therefore be evident that the 115 ejector 70 may be swung to the vertical position shown in full lines or to its upper horizontal position shown in dotted lines.

I will now describe the mechanism for reciprocating the scoop and at the same time 120 reciprocating the ejector. Connected to the hollow shaft 78 so as to rotate therewith is a spur gear 93 meshing with the gear 94 as shown in Fig. 4. The gear 94 is mounted on one end of a short longitudinal shaft 95 125 journaled in the bearing 96 and carrying loosely thereon the bevel gears 97 and 98 which are respectively associated with the clutches 99 and 100 connected by the cross-piece 101. Pivoted at 102 to the crosspiece 130

101 is a bell crank lever fulcrumed at 103 to the supplemental frame. By actuating the long arm 104 of this operating lever either the clutch 99 or 100 may be operated to 5 transmit motion to either the gear 97 or the gear 98, both of which are in mesh with the bevel gear 105. The gear 105 is keyed to a transverse shaft 106 extending entirely across the supplemental frame as shown in Fig. 3. 10 This cross shaft 106 carries spur gears 107, 107 near the outside lateral faces of the vertical plates 47, 47 of the supplemental frame as shown in Fig. 3. The gears 107 are in mesh with the rack teeth 108 of the upper 15 rack bars 69, 69. It is therefore evident that when the hollow shaft 78 is being rotated motion will be transmitted to the gears 93 and 94, the shaft 95 and the clutch members splined to the latter. When the lever 104 is 20 operated in one direction motion will be transmitted through the gears 98, 105, 107 and 108 to the rack bar 69 to effect movement of the ejector 70 in one direction, and when the lever 104 is moved in the other direction 25 motion will be transmitted to the gears 97, 105, 107, and 108 and the rack bar 69 to move the ejector in the opposite direction. The bodily forward and rearward movement, or reciprocating movements, of the ejector 70 30 are therefore fully under the control of the operator who actuates the lever 104.

At the same time that the ejector 70 is moved bodily in either direction the scoop 41 is moved in the opposite direction. The lateral gears 107, 107 are also in mesh with the teeth 109 of the rack bars 110, 110 which are suitably mounted below the rack bars 69, 69 on the supplemental frame. The rack bars 69 are mounted in suitable guideways 111, 40 111 and the rack bars 110 are mounted in similar guideways 112, 112.

The same lever 104 which is used for controlling the reciprocating movements of the ejector, is also used for controlling the reciprocating movements of the scoop 41 because whenever the cross shaft 106 together with the gears 107 thereon are operated the rack bars 69 and 110 are moved longitudinally in opposite directions. When the scoop 41 is 45 moved forward the ejector 70 is moved backward and when the scoop is moved backward the ejector is moved forward. When the scoop 41 is moved forward for the purpose of taking a load of coal or other material, the ejector 70 may be moved to its dotted line position shown in Fig. 1 so that when the scoop returns with the load the ejector will not interfere with the material in the scoop. By referring to the diagrammatic 50 illustration shown in Fig. 5 it will be seen that when the shovel 41' has been advanced to scoop up a load of coal from the platform or from the ground, and has been retracted to the position shown in full lines, the ejector 70' should be swung out of the way as

the load of material moves backwardly. The ejector 70' should then be lowered to the position shown in full lines and the rack gear operated so as to move the scoop forward at the same time that the ejector 70' is moved 70 backward. It will therefore be understood that simultaneously with the movement of the rack bars 110, 110 forwardly the rack bars 69, 69 are moved in the opposite direction. The apron 70' as shown in Fig. 5 not 75 only prevents the coal from being advanced with the shovel by acting as a stop or scraper, but also sweeps the coal rearwardly through the chute formed by the bottom and side walls of the supplemental frame, and into 80 the mine car 114 as clearly shown. In this arrangement the shovel is open ended and the coal is loaded into the mine car through one side of the latter as clearly indicated. This arrangement is particularly well-adapted 85 for operation in thin or shallow veins of coal where a particularly low frame work is necessary.

As before stated any suitable or convenient arrangement of gearing for positively swinging the ejector at will may be provided. When the scoop is being moved forward and the ejector is being moved bodily toward the rear, the latter may be rotated at the same time through a small arc of a circle. It 90 should be observed that the ejector may be swung from its dotted line position 113 in Fig. 5 to its full line position 70' without at the same time operating the rack mechanism; therefore the material in the forward 95 portion of the scoop may be pushed back effecting a partial unloading of the scoop into the chute before the scoop is moved forwardly again. Continued rotation backward 100 of the ejector after reaching its vertical position will effect a complete unloading of the scoop while the latter is being moved forward. 105

When worm gearing is used in connection with the ejector 70 as shown in Fig. 1, the 110 clutches 88 and 89 may both be released when the apron reaches its vertical position. The worm gearing will then act as a lock to prevent the forward rotation of the ejector when it engages the coal on the scoop. 115 In this manner the ejector may first be moved to the dotted line position 115 shown in Fig. 1 and then the scoop moved forwardly to take a load. After the scoop has been retracted to its initial position the rack mechanism may be stopped by placing the lever 104 in central position. Then by operating the lever 92 the ejector 70 may be swung down to its vertical position shown in full lines in Fig. 1, and left in such position, the worm gearing 71 and 74 acting as a lock to prevent further swinging of the ejector. Now, when the scoop moves forward the ejector 70 will be moved bodily 120 backward and will not only act as a stop 125 130

or scraper but also will act as a pushing plate to positively move the material backward into the chute of the supplemental frame. The relation of the parts may be 5 such that when the rear end of the scoop passes over the forward end 45 of the supplemental frame the ejector 70 will be a short distance back of the open end of the chute, thus insuring that all the material 10 will be pushed on to the bottom of the chute and not fall out on to the platform 43, or on to the ground if the platform is omitted. For this purpose the chute may be made 15 longer by extending the same farther forward. After the material is unloaded from the scoop and while the scoop continues forward to take another load, the ejector 70 is again swung to its dotted line position 115 as shown in Fig. 1, to permit the retraction 20 of the scoop to its unloading position. It should also be understood that when the scoop contains a load in its initial position and is then moved forwardly, the ejector 70 not only positively moves the material off 25 the scoop into the chute of the supplemental frame, but also positively moves all the material in the chute backwardly, some of it being moved at each operation into the mine 30 car 114.

The scoop 41 may be adjusted in elevation by means of the worm gearing and after 35 being so adjusted will be locked in adjusting position by reason of the worm gearing. It is therefore evident that if the platform 43 were omitted the lip 42 of the scoop would nevertheless be held off the floor any desired distance. Any resistance which the 40 floor might offer against the forward movement of the scoop would thereby be obviated. If no mechanism is provided for tilting the scoop or moving it to various adjusted positions, it may be connected rigidly to the 45 rack bars 110, 110 so as to be held off the floor any desired distance, as shown in Fig. 5.

In Fig. 7 I have shown a modification in that the supplemental frame 38" is permitted by its pivotal connection 37" with the main frame 9' to be tilted so that its forward end 45' rests on the floor. The scoop 41" is arranged to telescope into the chute of the supplemental frame and the sides of the scoop form the rack bars, the 55 upper edges of which are provided with rack teeth 109". The lip 42" rests directly on the floor but since the sides of the scoop may be guided in the chute so as to have no relative vertical movement thereto, the 60 coal may be picked up from the smooth surface without difficulty.

In Figs. 7 and 8 I have also shown a modification of the ejector mechanism. By means of the stop 116 the ejector 70" is pre-

vented from moving forward beyond its vertical position as shown in full lines in Fig. 7. It is free, however, to move backwardly into the dotted line position 150 as shown in Fig. 7. Therefore, when the scoop moves forwardly to take a load and then moves 70 rearwardly with the load the ejector will be moved upwardly by the material and then fall in front of the same back to its full line position or nearly so. Then when the scoop is moved forwardly again the stops 115 effectively prevent forward swinging movement of the ejector 70". Inasmuch as the 75 rack bar 69 moves backwardly at the same time that the scoop moves forwardly, the ejector 70" moves the material positively 80 back toward the rear end of the chute and thence into a mine car as shown in Fig. 5.

In order to increase the capacity of the scoop the supplemental frame is pivoted at 85 37 to the main frame and means provided for moving the supplemental frame laterally on the main frame. An arcuate rack 117 is mounted on the main frame as shown in Figs. 3 and 4. Meshing with the arcuate rack 117 is a pinion 118 at the lower end of 90 a vertical shaft journaled in the bearing 119 at one side of the supplemental frame. At the upper end of this shaft is mounted a bevel gear 120 which meshes with the bevel gears 121 and 122. The bevel gears 121 and 95 122 are mounted loosely on a shaft carried by the supplemental frame, and associated with these gears are friction clutches 123 and 124 connected by the crosspiece 125 and arranged to be operated by the lever 126 which is pivoted at 127 to the supplemental frame and connected by the link 128 to the crosspiece 125. The link 128 may be additionally supported by the pin and slot connection 129 if desired. When the lever 126 is moved down the clutch 124 will be operated and when the lever 126 is moved up the clutch 123 will be operated. The shaft 100 which carries the gears 121 and 122 has keyed to it a spur gear 130 which meshes with the gear 131 connected to the hollow shaft 54 as shown in Fig. 4. Therefore, when the hollow shaft 54 is rotated motion is transmitted through the gears 131 and 130 to the members of the clutches 123 and 124 105 115 which are splined to the shaft which loosely carries the gears 121 and 122. It is therefore evident that whenever the clutch 123 or 124 is operated motion will be transmitted in one direction or the other to the pinion 118 thereby effecting the movement of the supplemental frame on the main frame about its pivotal connection 37. Although 120 the spur gears 63, 62 and 86 are mounted on the main frame, lateral movement of the supplemental frame to either side from central 125 position will not interfere with the transmission of power to the scoop and

apron because of the flexible connections shown at 83, 84, 85 and at 59, 60, 61.

The present application is a continuation of my co-pending application, Serial No. 5 611,603 filed Nov. 10, 1896, so far as common subject-matter is concerned.

It should also be noted that the bottom of the scoop 41 constitutes a forwardly extending platform with an inclination which is 10 adapted to enter a horizontal kerf in a mine wall and dislodge a block of material which has been cut with kerfs above and below and on both sides thereof; this is particularly true if the platform 43 is omitted. While 15 the apron mechanism is preferred, the material may be delivered to the chute without the use of the apron 70. If the latter is omitted, or if it becomes broken, loading operations may nevertheless be carried on. 20 In such event the load may be gathered by the scoop and then retracted while the forward end thereof is lifted to a higher elevation so that the material will slide out of the scoop into the forward end of the horizontal chute and then be transferred in any desired 25 manner to the mine car in the position illustrated in Fig. 5. The scoop 41 may be tilted while in its initial position or while in any of its forward positions, and may therefore 30 be adjusted so that its bottom will act as an inclined plane for material to slide from the mine wall into the forward open end of the stationary chute. It should also be observed that the scoop is pivoted approximately 35 in vertical alignment with the rear delivery end of the chute so that the material may be gathered and delivered to the horizontal chute in a very low-roofed mine without the use of the apron, whenever desired. 40 It will also be noted that the scoop is pivoted on a transverse horizontal axis above the plane of the axis of the propelling wheels 10. The transverse horizontal axis of the propelling wheels is approximately 45 in a plane above the bottom 38 of the longitudinal chute, the forward end of which receives the rear end of the scoop, and the rear end of which extends into a mine car, as shown in Fig. 5. The material to be loaded 50 is therefore transferred along the chute back of the scoop between the wheels, and therefore along a path very near the floor of the mine chamber, as shown in Fig. 1.

Obviously those skilled in the art may 55 make various changes in the arrangement and details of the parts without departing from the spirit and scope of my invention as defined by the claims, and I desire therefore not to be restricted to the precise construction herein disclosed.

Having thus fully described an embodiment of my invention, what I wish to secure by Letters Patent of the United States is;—

1. In loading apparatus, the combination

with a scoop, of a chute directly back of said 65 scoop, means for moving said scoop forward to take a load and retract the same with the load to said chute, and means for moving the load off said scoop into said chute.

2. In loading apparatus, the combination 70 with a scoop open at its rear end, of means for reciprocating the scoop, and mechanism for unloading the scoop by pushing the material out of said open rear end.

3. In loading apparatus, the combination 75 with a scoop, of means for reciprocating said scoop, and worm gear mechanism directly connected to said scoop for adjusting the elevation of the forward end thereof and holding it in such adjusted position while 80 said scoop is reciprocated.

4. In loading apparatus, the combination with a scoop, of means for reciprocating said scoop, an ejector, and gearing for operating 85 said ejector to unload material from said scoop out of the rear end thereof.

5. In loading apparatus, the combination with a scoop open at its rear end, of means for reciprocating said scoop to take a load 90 of material and move it backwardly, an ejector, and means for operating said ejector to effect the unloading of the material from said scoop while it moves forward for the taking of another load.

6. In loading apparatus, the combination 95 with a scoop, of an ejector, and means for simultaneously reciprocating said scoop and said ejector in opposite directions.

7. In loading apparatus, the combination with a chute, of a scoop open at its rear end 100 and telescoping into said chute at the forward end of the latter, of means for moving said scoop bodily forward to take a load of material and retract said scoop with said load, an ejector, and means for operating 105 said ejector to engage the material in said scoop and move the same into said chute.

8. In loading apparatus, the combination with a scoop, of means for reciprocating said scoop, an ejector, and means for operating 110 said ejector to effect movement of material in said scoop out of the rear end of the same.

9. In loading apparatus, the combination with a main frame, of a supplemental frame comprising a chute, a scoop supported by 115 said supplemental frame, means for reciprocating said scoop, ejector mechanism for moving material from said scoop into said chute, and means for moving the supplemental frame together with the scoop laterally 120 on said main frame.

10. In loading apparatus, the combination with a main frame, of a supplemental frame pivoted to said main frame, a scoop supported by 125 said supplemental frame, apparatus for moving the supplemental frame laterally on its pivot together with the scoop, means for moving the scoop forward to take a load

- of material and retract the same with the load therein, and ejector mechanism for discharging the load of material from said scoop as it moves forward to take another load. 5
11. In loading apparatus, the combination with a chute, of a scoop open at its rear end and telescoping into the forward end of said chute when said scoop is in its initial position, of means for moving said scoop forward to take a load of material and retract the same to its initial position with the load, and ejector mechanism for moving the material off said scoop into said chute and along 10 the latter toward the rear end thereof.
12. In loading apparatus, the combination with a chute, of a scoop open at its rear end, means for reciprocating said scoop, and ejector mechanism for unloading the scoop into 15 said chute while said scoop goes forward for the taking of another load.
13. In loading apparatus for low-roofed mines, the combination with supporting framework, of a scoop, means for reciprocating said scoop rectilinearly relatively to 20 said supporting frame and while the latter remains stationary, and a device for pushing the load of material out of the rear end of said scoop.
14. In loading apparatus, the combination with a reciprocating scoop, of means for operating the same, and a device for effecting the unloading of material by pushing it from the rear end of said scoop. 25
15. In loading apparatus, the combination with a scoop, of means for operating said scoop to take a load, and to move the same back toward initial position for unloading the material on said scoop, and means for 30 effecting the unloading of the material in the scoop out of the rear end thereof while being moved forward again for another load.
16. In loading apparatus for low-roofed mines, the combination with supporting framework, of a scoop mounted thereon for movement relatively thereto and in advance of said framework, means for operating said scoop to gather a load, and a single 35 swinging device for effecting the unloading of material from said scoop by pushing action.
17. In loading apparatus, the combination with a reciprocating scoop, of an apron for unloading said scoop, and means for oscillating said apron to place it in position where it will not interfere with the load on the scoop when the scoop is moved rearwardly but will engage the material in the 40 scoop when the scoop is moved forwardly, to effect the unloading of the scoop from the rear end thereof.
18. In loading apparatus, the combination with a reciprocating scoop, of an apron, and means comprising gearing for positively actuating said aprons to move it into non-interfering position when the scoop with the load therein is moved rearwardly, and to move it into unloading position when the scoop is moved forwardly. 45
19. In loading apparatus, the combination with a scoop, of a device for engaging the material in the scoop to unload said material, oppositely actuated rack bars connected to said scoop and said device respectively, and means for reciprocating said rack bars. 50
20. In loading apparatus, the combination with a scoop, a device for engaging the material in the scoop to unload the same, a rack bar connected to said scoop, an additional rack bar connected to said unloading device, and means for simultaneously moving one rack bar in one direction and the other rack bar in the opposite direction 55 and reciprocating the movements of said rack bars.
21. In loading apparatus for low-roofed mines, the combination with a main frame, of a platform connected to said main frame to extend in advance thereof adjacent the floor of a mine chamber, a scoop mounted on said main frame for movement relatively thereto in advance of said frame and over said platform, means for operating said scoop to gather material from said platform, and mechanism for positively unloading said scoop by pushing the material out of the rear end thereof. 60
22. In loading apparatus, the combination with a main frame, of a platform connected to said frame, a scoop movable over said platform, means for operating said scoop to take a load, and mechanism for positively moving the load from the rear end of said scoop. 65
23. In loading apparatus, the combination with a scoop mounted for horizontal movement, of means for operating said scoop to take a load and return to initial position therewith, and mechanism for effecting the unloading of the scoop as the latter again moves forward. 70
24. In loading apparatus, the combination with a scoop, of means for operating the same, an apron, and means for operating said apron to move the same in one direction when the scoop moves forward and in the opposite direction when the scoop is returned. 75
25. In loading apparatus, the combination with a scoop open at its rear end, of means for reciprocating said scoop, and mechanism for positively moving the material off the scoop out of the rear open end thereof. 80
26. In loading apparatus, the combination with a main frame, of a supplemental frame pivoted to said main frame, a scoop carried 85

by said supplemental frame and movable laterally therewith, means for reciprocating said scoop relatively to said supplemental frame, and mechanism for dislodging the material from said scoop out of the rear end thereof.

27. In loading apparatus for low-roofed mines, the combination with supporting framework comprising a horizontal chute extending longitudinally, of a scoop mounted on said framework and movable relatively thereto in advance thereof, means for moving said scoop forward rectilinearly relatively to said chute and longitudinally thereof in advance of said framework to gather a load at the base of an upright mine wall, and mechanism acting independently of gravity by positively engaging the material in the scoop and unloading the latter into the forward receiving end of said chute.

28. In loading apparatus for low-roofed mines, the combination with a supporting frame, of a scoop mounted thereon for movement relatively thereto in advance of said frame, means for reciprocating said scoop rectilinearly to gather a load from the base of an upright mine wall and move it back therefrom, a trough on said framework behind said scoop into which trough the said scoop telescopes when in its initial position, and mechanism acting independently of gravity by positively engaging the material in the scoop to move such material from said scoop into said trough.

29. In loading apparatus, the combination with a scoop, of a trough, mechanism for operating said scoop to move the same forwardly to take a load and return the same to a position partially telescoping into said trough, and mechanism for pushing the material off the scoop and confining it to said trough when the scoop moves forwardly again.

30. In loading apparatus, the combination with a flat bottom scoop open at its rear end, of a trough open at both ends, means for reciprocating said scoop to take the load and return the same to a position where it partially telescopes into one end of said trough, an unloading device, and means for operating said unloading device.

31. In loading apparatus, the combination with a flat bottom scoop open at its rear end, of a trough open at both ends and telescoping at its forward end with the rear end of said scoop, an unloading device, mechanism for reciprocating the scoop for the purpose of taking a load and moving the same rearwardly to said trough, and unloading apparatus coacting with said reciprocating mechanism for preventing the material in the scoop again moving forward with the same and positively pushing the material off the scoop and along the trough

as the scoop moves forwardly from initial position.

32. In loading apparatus, the combination with a scoop open at its rear end, of a trough open at both ends and telescoping with the rear end of the scoop when the latter is in initial position, a rack bar connected to said scoop, an unloading apron capable of extending into the forward end of the scoop, an additional rack bar connected to said apron, means for reciprocating said rack bars and moving the same in opposite directions, and mechanism comprising gearing connected to said apron for moving the latter out of the way when the scoop moves rearwardly and to move the same into the front end of the scoop when the scoop moves forwardly and also to move said apron positively toward the rear to push the material off the scoop and along the trough toward the rear end thereof.

33. In loading apparatus, the combination with a main frame, of a supplemental frame pivoted to said main frame, a scoop carried by said supplemental frame, means for reciprocating said scoop, mechanism for moving the supplemental frame together with the scoop laterally, and a device for effecting the unloading of the material from the rear end of said scoop.

34. In loading apparatus, the combination with a scoop, means for operating the same to take a load and move it to unloading position, and a swinging device mounted so as not to interfere with the rearward movement of the load but offering an obstruction to its being moved forward with the scoop again and thereby effecting the unloading of the material from said scoop.

35. In loading apparatus, the combination with a scoop, of means for reciprocating said scoop, a swinging device extending into the forward end of the scoop when the latter moves forwardly from initial position, and means for moving said device to force the material off the scoop toward the rear.

36. In loading apparatus, the combination with a scoop, of means for reciprocating said scoop, a trough open at both ends and having its forward end telescoping with the rear portion of the scoop when the latter is in initial position, a swinging device offering an obstruction to the material on the scoop when the latter is moved forwardly from initial position, and mechanism for moving the said device rearwardly to move the material backwardly along the trough as the scoop slides forwardly under the material therein.

37. In loading apparatus, the combination with a main frame, of a platform connected to said main frame, a supplemental frame, a trough carried by said supplemental frame open at both ends, a scoop open at its rear

end and telescoping with the forward end of said trough when said scoop is in initial position, a rack bar connected to said scoop, an apron extending into the forward end of said scoop when the latter is in initial position, means comprising gearing for swinging said apron to give sufficient clearance to the material in the scoop when the latter is moving rearwardly with a load and to move said apron into the forward end of the scoop so as to offer an obstruction to the material being again moved forwardly with the scoop, a rack bar connected to said apron, and mechanism for reciprocating both of the aforesaid rack bars in opposite directions to effect the reciprocation of the scoop and the movement of said apron to positively push the material in the scoop and in the trough toward the rear into a mine car as the scoop moves forward for the taking of another load.

38. In loading apparatus, the combination with a main frame, of a supplemental frame pivoted to said main frame, a scoop mounted on said supplemental frame, means for reciprocating said scoop, and mechanism for dislodging the material from said scoop out of the rear end thereof.

39. In loading apparatus, the combination with a supporting frame, of a traveling scoop mounted on said frame for movement beyond the same while occupying a scooping position at the floor of the mine chamber, means for reciprocating said scoop rectilinearly and substantially parallel to the plane of the floor of the mine chamber while in a scooping position at the floor, to move the scoop forward beyond said frame to take a load of material and move the same back from the mine wall, and automatic mechanism for discharging the material from the scoop.

40. In loading apparatus, the combination with a frame, of a traveling scoop, means for reciprocating said scoop and causing it to take a load of material, and a pivoted scraper adapted to swing in one direction to permit the passage of the loaded scoop behind it, and provided with a stop to hold it in fixed position in front of the load for discharging the latter on the next forward movement of said scoop.

41. In loading apparatus, the combination with a supporting frame, of a traveling carrier, means for reciprocating said carrier and causing it to take a load of material, and mechanism acting on the material itself and moving it relatively to said carrier out of the rear end thereof toward loading position.

42. In loading apparatus, the combination with a chute, of a carrier open at its rear end and adapted to register with the forward end of said chute, means for re-

ciprocating said carrier, and mechanism 65 acting on the material on said carrier to move the same rearwardly out of the rear end of said carrier into said chute during the registry of the rear end of said carrier with the forward end of said chute. 70

43. In loading apparatus, the combination with a main frame, of a supplemental frame pivoted to said main frame for lateral movement relatively thereto, a scoop supported by said supplemental frame for 75 movement laterally therewith, apparatus for moving said supplemental frame laterally on its pivot together with said scoop relatively to said main frame, means for moving said scoop horizontally forward in 80 parallelism to the plane of the floor while occupying a scooping position at the floor to take a load of material and move the same back toward said frame, and mechanism for discharging the load of material from said 85 scoop and moving such material relatively to said main frame and while said scoop is moved forward to take another load.

44. In a loading machine, the combination with a truck, of a chute extending longitudinally between the wheels of said truck, a scoop mounted on said truck to extend in advance thereof and in alinement with said chute, means for moving said scoop forward parallel to the path of travel 95 of said truck, and means for moving the load out of said scoop into said chute and horizontally along the latter out of the rear end thereof.

45. In a loading machine, the combination with a scoop, of means for reciprocating said scoop, mechanism for adjusting the elevation of the forward end of said scoop, a chute extending horizontally back of said scoop and in alinement therewith, 105 and means for transferring the material from said scoop along said chute toward loading position.

46. In a loading machine, the combination with a chute, of a scoop open at its rear 110 end and telescoping into said chute at the forward end of the latter, means for moving said scoop bodily forward to take a load of material and retract said scoop with said load, and means for engaging the material in said scoop and moving such material into said chute.

47. In a loading machine, the combination with a chute, of a scoop open at its rear 115 end and registering with the forward end of said chute, means for moving said scoop forward to take a load of material and retract the same, and means for moving the material off said scoop into said chute and horizontally along the latter toward the 125 rear end thereof.

48. In a loading machine, the combination with a main frame, of a supplemental

- frame pivotally connected to said main frame for lateral movement, a scoop connected to said supplemental frame and extending in advance thereof, means for reciprocating said scoop to reach forward for loads in various arcuate positions, a chute back of said scoop and in alinement therewith in a general horizontal direction, and means for transferring the material in said 65
 10 scoop out of the rear end thereof into the forward end of said chute and horizontally along the latter toward the rear end thereof. 70
49. In a loading machine, the combination with a main frame, of a supplemental frame 15 pivoted on said main frame on an upright axis for lateral movement, a scoop pivotally connected to said supplemental frame on a transverse axis and extending horizontally in advance of said supplemental and main 20 frames, a chute mounted on said main frame and extending longitudinally thereof in a general horizontal direction from the front portion thereof to the rear, said chute being open at both ends and having its forward 25 end in registry with the rear end of said scoop when material is transferred from said scoop to said chute, mechanism for moving said scoop forward while in any of its various arcuate positions to gather material 30 in advance of said frames, and mechanism for effecting the transfer of the material from said scoop into said chute and along the latter toward loading position. 35
50. In a loading machine, the combination with a main frame, of a supplemental frame 40 pivotally connected to said main frame for lateral movement, a scoop connected to said supplemental frame and movable laterally therewith, a chute back of said scoop and in alinement therewith and extending horizontally and longitudinally of said main 45 frame from the front toward the rear thereof, propelling mechanism for moving said frames forward to force said scoop into material to be loaded, and mechanism traveling along said scoop relatively thereto for transferring the material out of the open rear end of said scoop into the forward open end of said chute and along the latter toward loading position. 50
51. In a loading machine, the combination with a supporting frame, of a channel 55 extending longitudinally thereof with its forward receiving end and its rear delivery end open, with the space between the forward receiving end and the base of the mine wall free and unobstructed for the passage of material to be loaded directly from the base of the mine wall into the receiving end of 60 said channel, the bottom of said channel being located adjacent the supporting surface over which said machine operates and lying in the same horizontal plane throughout its length, and means for supporting 65 said frame and said channel with the bottom of the latter in such position for passage of the material from the base of the mine wall along said channel in a general horizontal direction to the delivery end of 70 said channel. 75
52. In a loading machine, the combination with framework comprising a channel for the passage of material to be loaded, of means for propelling material through said channel, and wheels located on opposite sides of said channel for supporting said framework, the axles for said wheels being located above the plane of the bottom of said channel and terminating outside of said channel at the sides of said framework. 80
53. In a loading machine, the combination with framework, of supporting wheels on opposite sides thereof, and a conduit for material to be loaded extending between said wheels and having the bottom thereof located below the axes of said wheels throughout the entire length of said conduit, said framework being free and unobstructed in the space between the forward receiving opening of said conduit and the base of an upright mine wall to permit movement of material directly from such mine wall base in a general horizontal direction into the receiving opening of said conduit. 85 90
54. In a loading machine, the combination with a supporting frame, of means extending in advance of said frame along a free and unobstructed space at the base of a mine wall for receiving material from said space and lifting such material a slight distance above the surface on which it rested, and means for conveying said material to loading position and for discharging said material into a receptacle for transportation, said conveying and discharging means being arranged to transport said material upon the same level to which it is raised by said lifting means and in a general horizontal direction. 95 100 105
55. A machine for loading material in a mine chamber comprising framework having a passageway extending longitudinally thereof with the space between the receiving end of said passageway and the upright face of the mine wall free and unobstructed, the floor of said passageway being on substantially the same level throughout its entire length and located adjacent the flow of the mine chamber, the forward end of said floor being in position to permit movement of material from the floor at the base of said mine wall into the passageway, and means for effecting the transfer of material along said passageway adjacent the floor of the mine chamber and discharge from the rear end of said passageway into a transporting receptacle. 110 115 120 125
56. In a loading machine, the combination

- with a channel-shaped frame having both ends open with the forward receiving opening being adapted to receive material from a free and unobstructed space between said receiving opening and the floor at the base of an upright wall in a mine chamber, of means for movably supporting said frame with the bottom portion of the channel thereof in close proximity to the surface 10 upon which said machine rests, means for causing material on the floor at the base of an upright mine wall to enter the receiving opening of said channel, and means for transferring said material through said 15 channel and discharging such material from the other end thereof.
57. In a loading machine, the combination with a receptacle having side walls and adapted for transporting material, of a loading chute entering said receptacle in position to discharge material thereinto below the upper edges of said side walls, and loading mechanism for gathering material from the floor at the base of an upright mine wall 20 and transferring such material along lines adjacent the floor of the mine chamber through said chute into said transporting receptacle.
58. In a loading machine, the combination with a flat bottom scoop open at its rear end, of a substantially horizontal trough open at both ends and in alignment with said scoop, with its forward end registering with the rear open end of said 25 scoop, means for reciprocating said scoop to gather material, and unloading mechanism for transferring the gathered material from said scoop into said trough and along the latter horizontally toward loading position.
59. In apparatus for picking up coal from a mine floor at the bottom of the face and taking it to remote points for delivery, the combination of a wheeled car with a relatively low floor and a receiving opening in its rear end extending to relatively low horizontal planes, a frame separable from but adapted to align with said car, means supported on said frame adapted to move 30 under and engage with loose coal and carry it on low horizontal lines toward said loading opening, and devices on said frame adapted to positively eject the coal from the means aforesaid and cause its entrance on substantially the last aforesaid low horizontal line through the said opening into said car.
60. In loading apparatus, the combination with a frame having a passageway extending along relatively low horizontal lines from a forward receiving opening to a rear delivery opening, of means mounted on said frame in position to move under and engage 35
- with loose coal at the base of an upright mine wall in advance of said passageway, and mechanism mounted on said frame for effecting the transfer of the coal from said engaging means into the receiving opening of said passageway and along the latter on low horizontal lines to the delivery opening of said passageway for loading into a mine car having a bottom extending to such low delivery opening.
61. In an apparatus for removing loose coal from a mine floor and taking it to remote points for delivery, the combination of a wheeled car having a front end wall and side walls normally closed, and a receiving opening at its rear end extending to the horizontal line near the floor, a frame separable from the car, means for supporting the loose coal in the pathway extending along low horizontal lines near the mine floor, means for causing coal to travel backward along the forward part of said pathway, and a horizontally reciprocating pusher plate adapted to be held rigidly and approximately vertically while moving operatively in one direction and free to swing upward vertically when moving idly in the opposite direction, and adapted when moving in the first aforesaid direction, to engage with the coal in said pathway and cause its outward movement through the rear part of said pathway on the aforesaid low horizontal lines through said opening to the interior of said car.
62. In loading apparatus, the combination with framework having a pathway extending along low horizontal lines near the mine floor from a forward open receiving end to a rear open delivery end, of means for gathering a load of material in advance of said framework at the base of an upright mine wall, and mechanism comprising a vertically hanging pusher plate held from swinging forwardly beyond its vertical position but free to swing rearwardly therefrom, for engaging the coal on said gathering means and moving such coal therefrom into the receiving opening of said pathway and along the latter adjacent the mine floor to the delivery opening of said pathway for loading into a mine car having a receiving end extending to a horizontal line near the floor of the mine chamber.
63. In loading apparatus, the combination with a supporting frame, of a traveling shovel mounted thereon for movement relatively thereto, means for reciprocating said shovel relatively to said frame and thrusting it into a mass of material at the base of a mine wall in a space free and unobstructed by any part of said frame, and a pivoted scraper mounted on said frame in the path of movement of the load of said

shovel and adapted to swing in one direction to permit the passage of the loaded shovel behind it and provided with a stop to hold it in fixed position in front of the 5 load for discharging the latter on the next forward movement of the said shovel.

In testimony whereof I have signed my

name to this specification, in the presence of two subscribing witnesses, on this 1st day of September A. D. 1914.

EDMUND C. MORGAN.
